(57) **CLAIM**

I claim the ornamental design for an apparatus for securing a work piece, as shown and described.

DESCRIPTION

FIG. 1 is a perspective view of an apparatus for securing a work piece according to my new design, the broken lines of the apparatus for securing a work piece are for illustrative purposes only and form no part of the claimed design;

FIG. 2 is an exploded view of the apparatus for securing a workpiece of FIG. 1, the broken lines of the apparatus for securing a work piece are for illustrative purposes only and form no part of the claimed design;

FIG. 3 is a front elevational view of the apparatus for securing a work piece of FIG. 1, the broken lines of the apparatus for securing a work piece are for illustrative purposes only and form no part of the claimed design;

FIG. 4 is a rear elevational view of the apparatus for securing a work piece of FIG. 1, the broken lines of the apparatus for securing a work piece are for illustrative purposes only and form no part of the claimed design;

FIG. 5 is a left side elevational view of the apparatus for securing a work piece of FIG. 1;

FIG. 6 is a right side elevational view of the apparatus for securing a work piece of FIG. 1; and,

FIG. 7 is a top plan view of the apparatus for securing a work piece of FIG. 1.
